CLAIM

The ornamental design for a camera light, as shown and described.

DESCRIPTION

FIG. 1 is a front view of camera light showing our new design;

FIG. 2 is a rear view thereof;

FIG. 3 is a right view thereof;

FIG. 4 is a left view thereof;

FIG. 5 is a bottom view thereof;

FIG. 6 is a top view thereof;

FIG. 7 is a perspective view thereof; and,

FIG. 8 is perspective view thereof, shown in an alternate configuration of use.

The broken lines in the drawings depict portions of the camera light that form no part of the claimed design.

1 Claim, 8 Drawing Sheets
